Fig. 1

Fig. 2

Fig. 3

Fig. 4

FIG. 1 is a front elevational view of a sugar bowl or the like embodying my new design, with the ornamentation on the back elevational view being identical.

FIG. 2 is a top plan view.

FIG. 3 is a side elevational view with the opposite side view being a mirror image except for the notch in the lid.

FIG. 4 is a fragmentary developed view of the ornamentation of FIG. 1.

The characteristic feature of the design resides in the particular ornamentation applied to the outer wall as shown.

I claim:

The ornamental design for a sugar bowl or the like, as shown and described.
